UNITED STATES PATENT OFFICE.

MELVAN L. TWOMLEY, OF ANDERSON, INDIANA.

MACHINE FOR PARAFFINING CARTON-BLANKS.

1,045,222.

Specification of Letters Patent. Patented Nov. 26, 1912.

Application filed September 6, 1910. Serial No. 580,673.

To all whom it may concern:

Be it known that I, MELVAN L. TWOMLEY, a citizen of the United States, residing at Anderson, in the county of Madison and State of Indiana, have invented certain new and useful Improvements in Machines for Paraffining Carton-Blanks, of which the following is a specification.

My invention relates to the art of coating blanks from which cartons are to be made with paraffin. After the paraffin has been applied and the blanks are cut to shape they are creased and bent up to shape, the meeting edges of the blank overlapped and glued together. Heretofore the paraffining has been done by a pair of rollers, the one which applies the paraffin being grooved circumferentially at suitable distances along its length to leave untreated strips on the blank where the glue is to be applied. Usually the lower roll dips into a bath of paraffin and applies it to the cardboard which is passed in the form of sheets between the rolls and subsequently cut up to form carton blanks which are then bent up and glued, as above stated. One edge of each sheet is made to extend over the groove in the applying roll, whereby it is left free of paraffin so that it may readily take the glue which is subsequently applied. It has been found, however, in practice not only difficult to feed such strips with sufficient accuracy so that no paraffin is spread upon the edge strip which is intended to be reserved for glue, but also very difficult to properly regulate the flow of such an amount of wax as is required to treat large sheets and when sheets are treated by the above method and then stacked there is a tendency for the wax to off-set from one sheet to the other, thereby applying some wax to the edge which should be reserved for glue, and further, when the sheets are paraffined by the above method, the entire sheet being treated with the exception of the edges reserved for glue, it is found that thereafter when the sheets are being cut in cartons much difficulty is encountered by reason of the wax adhering to the cutting die and filling the creases which produce the scores in the carton. It also follows that by the above method not only the carton is paraffined but also the waste paper which must be stripped away from the carton, the paraffin applied to the waste paper being lost. The waste paper is sold to the

paper mills and the wax on this paper is objectionable and waste paper thus treated is less valuable than unwaxed waste.

In paraffining by the above method it has been the custom to space the grooves on the lower roller apart from each other a distance which would leave untreated the glue strips on two or three rows of standard size one-pound butter cartons. It will be noted, therefore, that this machine is efficient only for paraffining sheets which contain cartons of the exact size for which the rolls are grooved.

In the machine which forms the subject matter of my present invention the cardboard is not paraffined in the strip or sheet but this operation is performed after the sheet has been cut up into carton blanks. I have found my machine to apply the paraffin with greater accuracy than was possible with the machines heretofore used and by the provision of the features which will be pointed out in the detailed description and covered in the claims an even coating of the desired thickness is obtained without distributing the wax on the portion of the carton blank reserved for glue, and furthermore it is possible to operate upon a great deal more material in the same space of time than in the old machines and with less attention on the part of the operator employed in running the machine.

In my machine its highest efficiency is maintained in making cartons of any size and as the cartons are paraffined after being cut there is no paraffined waste paper and in the operation of cutting there is eliminated the problem encountered when cutting sheets that have previously been paraffined.

In the drawings accompanying this specification, Figure 1 is a plan view of my machine; Fig. 2 a side elevation; Fig. 3 a vertical section on the line 3—3 of Fig. 1; Fig. 4 a vertical section on the line 4—4 of Fig. 3 looking in the direction of the arrows; Fig. 5 a vertical section on the line 5—5 of Fig. 3 looking in the direction of the arrows; Figs. 6 and 7 fragmentary views in elevation and horizontal section respectively of a doctor forming a part of my machine, a part being shown in section in Fig. 6; and Fig. 8 represents a carton blank showing the area to which paraffin is applied and that left free of wax for the subsequent application of glue.

In the carton blank shown in Fig. 8, for the purpose of aiding in an understanding of my invention the letter A refers to the body thereof, which is provided at one edge 5 with a lap B which is coated on one side with glue and a strip C on the other edge and on the other side of the paper free from the paraffin with which the body of the blank is covered, to which strip the lap B is 10 to be cemented.

In the embodiment of my invention shown the machine is in part in duplicate for the purpose of feeding two series of blanks at the same time through the rolls, but it will 5 be evident that a single series can be fed at a time without altering the machine or if desired, by an obvious mechanical adjustment of the machine, it may be adapted for but a single series.

The frame 9 is provided with standards 10 for supporting the same and these parts may be of any suitable design. The cardboard is fed between an upper and a lower roll 11, 12, the latter of which dips into a bath 13 of paraffin which is kept in a suitable state of fluidity by a steam jacket 14 beneath the pan. A pipe 15 with a valve 16 is shown for draining the tank. The rolls 11, 12 are also heated by steam with which 5 the pipes 17, 18, located in the interior of the rolls, are supplied. These steam pipes are located in the lower part of the rolls and are bent upwardly and then outwardly, extending through hollow journals 19, 20, 10 respectively, of the upper and lower rolls and are connected to a common supply pipe 21. The lower roll is stationarily mounted in its bearings 22, 23, but the upper roll is mounted in sliding bearings 24, 25 and is pressed into contact with the lower roll by springs 26, 27 which are adjustable by hand wheels 28, 29 in the usual manner for regulating the pressure between the rolls. In order to permit of the relative 5 adjustment of the rolls a telescoping joint may be made in the pipes connecting the steam supply to the heating pipes of the rolls, as at 32, see Fig. 5. A supply tank 33 is mounted above the tank 13 which supplies 10 paraffin to the lower roll and communication between the two is effected by a pipe 34 controlled by a hand valve 35. The paraffin in the supply tank is maintained in a fluid condition by steam pipes 36 located near the lower corners on opposite sides of the tank. Guides 37, 38, supported from the ends 39, 40 of the frame support the blanks as they are discharged from the rolls and deliver them to a receiving table to be described. In 15 order to regulate the thickness of the wax layer applied to the carton by roll 12 it is supplied with a doctor 41 which is adjustable through screw rods 42, 43, at opposite ends thereof. These screw rods are threaded at their ends into tapped sleeves 42' which

are pivoted to the ears 44 attached to the back of the doctor. The latter is pivoted, as at 45, and provided with a face or lining plate 46 which may be, and preferably is, of a different material from the body of the doctor, such as brass, and formed with a longitudinal rib 47, the edge of which is adjusted to scrape off superfluous wax from the roll 12. In order to insure an even thickness of wax throughout the length of the roll it is necessary to accurately adjust the liner at various points along its length. For this purpose I provide screws in pairs at suitable intervals in the length of the doctor, one of each pair engaging a tapped bore in the body of the doctor and bearing upon the surface of the lining to press it away from the doctor and the other passing freely through the body of the doctor tapped into the lining and adapted to draw the lining toward the body of the doctor in a manner which will be obvious. These screws, numbered 48 and 49, respectively, and the swivel head 50, are best shown in Figs. 6 and 7, the swivel head in the former figure being shown in dotted lines.

As each carton blank passes between the rolls a certain proportion of the wax on the lower roll is prevented from passing between the carton and the lower roll and banks up at the entry to the bite of the rolls. When the carton passes out of the rolls, relieving the passage between them, this wax is frequently transferred to the upper roll and unless provision were taken for its removal it would form irregular masses thereon and be applied to the upper face of the succeeding blanks. In order to prevent this I have provided a scraper blade 51 which bears upon the upper roll and is attached to the upper edge of a pivoted trough 52 to receive the scrapings from the roll. The trough is swiveled at its ends upon the pipe sections 52', 52'' extending through the sides of the frame, the former of which 100 opens into the trough and is connected to piping 53, 54 leading to a point above the bath or tank 13. This system of piping serves to return the fluid wax from the trough to the bath 13. The steam pipe section 52 extends substantially the length of the trough and at one end is reduced to a small steam heating pipe which extends through the pipes 53 and 54 to heat them and retain the wax in the trough and in the 105 return pipe in fluid condition. The trough is provided at its ends with upwardly-extending arms 55 connected by springs 56 to the roll housings 57 to hold the scraper in close contact with the upper roll. The carton blanks are fed to the rolls by two series of endless belts or aprons 58, 59, both driven from the same roll 60 at the feed end of the machine. The belts of the first series pass around a roll 61 located as closely as is 110 115 120 125 130

practicable to the bite of the treating rolls 11, 12. The intermediate belts 59, to-wit those of the second series, are shorter than the belts 58 and pass around a roll 62 which is located at a point more remote from the treating rolls for a reason which will appear. The roll 62 is reduced at suitable intervals for the passage of the longer belts 58. The belts of the series form the bottom of a hopper or to speak more accurately in relation to the present machine of a pair of hoppers, the side walls of which are formed by the adjustable partitions 63. These side walls are supported on hollow posts 65 which are adjustable crosswise of the machine upon slotted bars 68, 69. The standards 65 are formed at their lower ends with enlargements 67 which engage the upper faces of slotted bars 68, 69, and with screws 64 which pass through the slots 70 and engage nuts 66, beneath them. It will be clear that by means of the said screws the sides of the hoppers can be accurately fixed upon the cross bars, their positions being determined by the width of the carton blank and with reference to the ends of the rolls. When adjusted for use the outside walls of the hoppers occupy vertical planes slightly beyond the ends of the rolls so that the carton blanks in passing through the rolls project a sufficient distance beyond the ends thereof to leave the unwaxed strip above referred to, for glue. The forward end of each hopper is open but the rear end is formed of pairs of angular abutments 71, the faces of which slope inwardly toward the bite of the treating rolls and terminate short of the endless belts. The lower ends of the abutments are in effect continued by adjustable members 72 whose distance from the belts may be accurately fixed. The adjustable members are slotted as at 73 to receive studs 74 mounted on brackets 75, attached to the cross-piece 76 by suitable bolts. The vertical position of the adjustable members is determined by thumb-screws 77 passing through an angular portion thereof and bearing upon the stationary brackets 75. The roll 60 for driving the belts which form the bottoms of the hoppers is mounted at its ends in suitable bearings 78 and one of its trunnions projects outwardly beyond the side of the frame and carries a driving pulley 79. The treating rolls are provided on their corresponding ends with intermeshing gear wheels 80, 81, and the lower roll with a belt pulley 82 which drives a belt 83 extending over the pulley 79 and hence the aprons of the blank-feeding device. An idler 84 is mounted on a lever 85 for taking up slack in the belt. The gears on the ends of the treating rolls are driven through the lower gear 81 by means of a gear 86 mounted on the power shaft 87 which carries a suitable fast and loose pulley 88 for trans-

mitting power thereto. The receiving table consists of an endless apron 89 mounted on rollers 90, 91, supported in brackets 92, 93, which are adjustable along horizontal rods or tubes 94. Standards 95 support the outer ends of these horizontal rods or tubes, the inner ends of which are attached to brackets 96 on the framework. The upper run of the belt of the receiving table is supported on a plate 97 which rests on the upper ends 75 of standards 98, also adjustable longitudinally of the rods or supports 94. The endless belt 89 is driven from the power shaft through the twisted belt 98, reducing pulleys 99, 100, belt 101 and pulley 102 on the 80 journal of the roll 90.

I have found in practice that as the following edge of the blank leaves the bite of the rolls it is apt to splash paraffin in the direction of the feed belts or aprons. The latter are composed of rubber and it is desirable to preserve as much as possible their frictional surface which would be materially interfered with by a coating of paraffin. In order to obviate the coating of these belts I 90 interpose between their rear ends and the treating rolls a screen which is preferably in the form of a pipe 103 of considerable diameter extending across the machine. With this pipe is connected a smaller steam pipe 95 104 which is fed by a pipe 105 from any suitable source of steam. It follows from this construction that any drops of melted paraffin which are thrown back by the carton blank or treating rolls and are caught 100 by this pipe, their fluidity being maintained by the heat thereof, are sooner or later dropped into the vat 13. While the pipe 103 catches any drops of considerable size finer particles may find their way beyond it 105 and into contact with the longer belts but the shorter belts being more remote receive no paraffin whatever and their frictional surface is unimpaired.

In operation the blanks are stacked in the 110 hoppers, as shown in Fig. 3, and when the machine is in operation the lowermost blank is fed by the belt to the treating rolls and is followed by the successively superposed blanks in order. The friction of the shorter 115 belts is sufficient for this purpose even though the longer belts be rendered less effective by a film of paraffin. In the double feed machine illustrated two stacks of blanks are supplied, one in each hopper, and 120 are fed in two streams through the rolls, the outer edge of each blank projecting beyond the roll end a sufficient distance to leave uncoated a strip to receive the glue employed in securing the box. If it be desired to paraffin the other sides of the blanks they are simply reversed and again passed through the machine.

My machine is capable of treating a greater quantity of material than any ma- 130

chine heretofore employed and is more accurate in preserving the line between the coated area and the strip reserved for glue, and furthermore it requires less attention than any machine for the same purpose with which I am acquainted.

What I claim is:

1. In a machine of the class described, the combination of a pair of treating rolls, a hopper for feeding blanks thereto, the bottom of which is composed of two series of endless belts, one of which series passes about a roll located close to the bite of the rolls, the other of which series of belts passes about a roll located at a distance from the treating rolls, and means for drying both series of belts.

2. In a machine for applying paraffin to cartons, the combination of a pair of treating rolls, endless belts for feeding carton blanks thereto, and a screen extending substantially the length of the rolls interposed between the belts and the treating rolls.

3. In a machine of the class described, the combination of a pair of treating rolls, endless belts for feeding cartons thereto, a screen interposed between the belts and the rolls, and means for heating the screen.

4. In a machine of the class described, a pair of treating rolls, endless belts for feeding cartons to be treated thereto, a pipe interposed between the rolls and the nearest point of travel of the belts, and a steam-pipe connected with said pipe for heating it.

5. In a machine of the class described, a pair of rolls for applying wax to cartons, a scraper for removing wax from one of the rolls, and means for heating the scraper.

6. In a machine of the class described, the combination of a pair of rolls for applying paraffin to a carton, a scraper for removing wax from one of the rolls, and means for heating the scraper.

7. In a machine of the class described, the combination of a pair of rolls for applying wax to cartons, a scraper for removing wax from one of the rolls, a receptacle or conduit for receiving the wax removed from the scraper, and means for heating the scraper and conduit.

8. In a machine of the class described, the combination of a pair of rolls for applying paraffin to cartons, a tank for supplying paraffin to one of the rolls, a scraper, a conduit or receptacle for receiving wax from the scraper, means for heating the conduit,

and connections for returning the molten wax to the paraffin tank.

9. In a machine of the class described, the combination of a pair of rolls for applying wax to carton blanks, endless belts for feeding the same, and a guide arranged laterally beyond the ends of the rolls to feed the blanks with their edges extending beyond the ends of the rolls.

10. In a machine of the class described, the combination of a pair of rolls for applying paraffin to cartons, a tank for supplying paraffin to one of the rolls, a scraper, a conduit for receiving the wax from the scraper, pipe connections from the conduit for returning the molten wax to the paraffin tank, and a steam pipe in the conduit and pipe connections for heating the same.

11. In a machine of the class described, the combination of a pair of rolls, means for supplying one of the rolls with coating material, a hopper for receiving sheets of material to be coated, the bottom of which is formed of endless belts, some of which belts extend around a roller arranged parallel to and in proximity to the coating rolls and others of which pass around a roll more remote therefrom, and a screen interposed between the bite of the coating rolls and the belts.

12. In a machine of the class described, a coating roll, a pivoted doctor for controlling the thickness of coating material thereon, screws connected to the doctor for adjusting it toward and away from the roll, a face plate 46 upon the doctor having a ridge 47 for scraping off superfluous wax, a series of screws bearing upon the face plate, and a second series of screws threaded into the face plate, the two series coöperating to adjust the face plate with reference to the body of the doctor.

13. In a machine of the class described, the combination of a pair of rolls comprising a top roll and a paraffin-applying roll, a tank beneath the latter in which it dips, a doctor for controlling the thickness of material on the roll and a face plate on the doctor adjustable toward and from the body thereof and formed with a longitudinally extending rib.
